UNITED STATES PATENT OFFICE.

GEORGE W. ROBERTS, OF PATTONVILLE, TEXAS, ASSIGNOR OF ONE-HALF
TO NOAH M. RISH, OF SAME PLACE.

COTTON CHOPPER AND HARROW.

SPECIFICATION forming part of Letters Patent No. 269,716, dated December 26, 1882.

Application filed June 17, 1882. (No model.)

To all whom it may concern:

Be it known that I, GEORGE W. ROBERTS, a citizen of the United States, and a resident of Pattonville, in the county of Lamar and State 5 of Texas, have invented a new and valuable Improvement in Cotton Choppers and Harrows; and I do hereby declare that the following is a full, clear, and exact description of the construction and operation of the same, reference being had to the annexed drawings, making a part of this specification, and to the letters and figures of reference marked thereon.

Figure 1 of the drawings is a plan view of my device. Fig. 2 is a side view with the near 15 wheel removed. Fig. 3 is a cross-sectional view on line $x x$, Fig. 1. Fig. 4 is a plan view, showing the harrow attached, and Fig. 5 is a side view of the harrow attachment.

This invention has relation to cotton choppers and harrows; and it consists in the construction and novel arrangement of parts, as will be hereinafter fully described and claimed.

Referring by letter to the accompanying drawings, a designates the axle, and $b b$ the supporting-wheels. Converging and slightly curved arms $c c$ are let into recesses $d d$ in the upper face of the axle a , and are secured at their forward ends to a straight arm, e , let into a middle recess, f , in the upper face of the axle a , as 25 shown in the drawings. These three arms $c c$ and e are hinged near their juncture, and are let into recesses $g g g'$ in the under face of a lateral bar, h , from the ends of which vertical standards $i i$ depend, as shown.

Upon the arms $c c$ and e , between the lateral bar h and the axle a , are secured curved racks k , and to one side of each of said arms is pivoted a hand-lever, l , engaging said racks k . From the hand-levers l chains m extend over 35 sheaves n , pivoted on standards o , the rear ends of said chains m being adapted to engage the beams of the harrow or cotton-chopper sections. Referring first to the cotton-chopper sections, of which there are three, designated 40 by the letters $p p$ and p' , the former being the side sections and the latter the central one, which latter has two longitudinal beams, q , while the side sections have but one beam, q' , it will be seen from the drawings that these 45 beams q and q' are hinged at their forward

ends, by strap-loops r , to a cross-bar, s , which is designed to be detachably attached to the lower ends of the depending standards $i i$, which, by the way, are strengthened by braces $t t$, extending from near their lower ends upwardly and rearwardly to the under face of the axle, to which they are secured by bolts or otherwise.

The rear ends of the beams $p p$ and p' are provided with section-bars $u u$ and u' , the latter being the central section-bar. From these section-bars depend forwardly-curved and pointed standards v , threaded at their upper ends to receive securing-nuts v' , and provided at their lower ends with forwardly-inclined 65 knives w , as shown.

From the beams q of the central section, p' , handles $x x$ extend rearwardly and upwardly, and are bolted to standards $z z$, rising from the central section-bar, u' , and connected near 70 their upper ends by a double rack, a' , serrated near each end in its forward edge, the serrations pointing inwardly from said standards $z z$. Braces $b' b'$ extend forward from the under face of the central section-bar, u' , near each 75 end, to the under faces of the beams q of the central section, p' , to add additional strength. Levers $c' c'$ are pivoted at their lower ends to the front face of the central section-bar, u' , and near the ends thereof, and extend upwardly 80 above the double rack a' and engage the serrations of the same.

From the levers $c' c'$, slightly below their middle portions, pivoted perforated arms d' extend, and are connected by pivots e' to the inner or 85 forward faces of the side section-bars, $u u$, as shown, the object of the perforations in said arms being to permit a greater lateral adjustment of the bar-sections than could be accomplished by the use of the levers $c' c'$ alone when 90 it is desired to leave larger or smaller cotton-stands.

Standards f' depend from the beams $q' q'$ and from a cross-bar, g' , connecting the beams q of the central section, u' , and are provided at 95 their lower ends with wheels h' , which ride over the ridges in advance of the knives and prevent the latter from cutting too deeply, and thereby impeding the draft of the implement. The chains, with their levers, racks, and sheaves, 100

permit the knives and wheels h' to be elevated and permitted to remain inoperative when the implement is being transported from place to place. The chopper is to be driven across the 5 ridges, the cotton-stands being left between the knives, the portions not needed being cut away by the knives. In cultivating the cotton the chopper-sections are removed by detaching the cross-bar s from the standards $i i$, and 10 the cross-bar i' of the hinged harrow-sections $k' k'$ is secured to said standards.

The beams $l' l'$ of the harrow-sections are secured to the cross-bar i' in a manner similar to the beams of the chopper-sections, and are 15 provided with converging tooth-bars $m' m'$ and handles $n' n'$, as shown. Connections for the elevating-chains are also provided, in order that the harrow-sections may be rendered inoperative when desired. The teeth of the harrow-sections may be of any ordinary construction, or may be of the conformation shown in the drawings, which is preferable. The whiffle-tree is preferably connected to the under face of the arms $c c$ and e at their juncture, but 20 may be otherwise connected.

The operation of the combined implement is obvious to any one skilled in the industry to which it appertains when taken in connection 25

with the foregoing description and the accompanying drawings.

Hinged beams carrying teeth and cutting-blades and provided with levers and connecting-bars have been before used in cultivators, cotton-choppers, &c., and are not broadly claimed herein.

Having thus fully described my invention, what I claim as new and useful, and desire to secure by Letters Patent of the United States, 30 is—

In a cotton-chopper, the combination, with 40 the wheeled vehicle, of the side and central section-bars carrying the inclined knives, the handles secured to the central section, the double rack connecting said handles, the adjusting-levers pivoted to the central section, and 45 the pivoted perforated arms connecting the levers and outer section-bars, substantially as described.

In testimony that I claim the above I have hereunto subscribed my name in the presence 50 of two witnesses.

GEORGE WHITFIELD ROBERTS.
